UNITED STATES PATENT OFFICE.

WILLIAM KEELY, OF GRAYBURG, TEXAS.

BENDING-MACHINE.

Specification of Letters Patent.

Patented Nov. 5, 1918.

1,283,794.

Application filed May 29, 1917. Serial No. 171,671.

To all whom it may concern:

Be it known that I, WILLIAM KEELY, a citizen of the United States, residing at Grayburg, in the county of Hardin and State of Texas, have invented certain new and useful Improvements in Bending-Machines, of which the following is a specification.

The machine which is the subject matter of the present application for patent, is designed for straightening railway rails, and the object of the invention is to provide a simple, efficient and easily operated fluid-pressure actuated machine of this kind as will be pointed out in the detailed description appearing hereinafter.

In order that the invention may be better understood, reference is had to the accompanying drawing, forming a part of this specification.

In the drawing—

Figure 1 is a plan view of the machine, and

Fig. 2 is an end view of a fluid-pressure cylinder.

Referring specifically to the drawing, 10 denotes a steam or other fluid pressure cylinder in which works a reciprocating piston 11 having a rod 12 which is connected to a 15 cross head 13 slidably mounted on a guide rod 14. To the side of the cross head 13 is pivoted, as shown at 15, one end of a lever 16 having its other end fulcrumed, as shown at 17, to a rod 18 carried by a frame 20 work to be presently described. To the lever 16, intermediate its ends, is pivotally connected, as shown at 19, a ram 20, having a head 21 which engages the work to be straightened. The machine is designed more 25 particularly for straightening railway rails, although it is not limited to such, but may, with equal facility, be used for straightening bars, pipes, shafting, and other parts.

A fragment of the rail or other part to be straightened is shown at 22. This rail is laid alongside a former 23 consisting of a stout, straight beam or other abutment braced against timbers 24. The rail is laid so that the bend to be straightened out is 30 opposite the ram head 21, and then fluid pressure is admitted to the cylinder 10 to advance the piston 11, whereupon the ram 20, through its connections with the piston, is advanced, and the head of the ram bends 35 the rail straight in an obvious manner.

In order that the rail 22 may be easily

shifted in the direction of its length, it is supported on rollers 25 journaled in the beam 23 and a beam 26 extending parallel thereto in spaced relation.

To an upright timber 27 at the side of the beam 26 is secured a guide 28 through which the ram 20 passes, and which prevents the ram from being deflected up or down, the guide being bored tapered to allow the side swing of the ram according to the swing of the lever 16. The connection between the lever 16 and the rod 18 is a slotted one so that the lever may swing freely when the piston 11 is moving.

The cylinder 10 is securely bolted to one side of a heavy timber 29, it having a flanged base for this purpose as shown at 30. A rod 31 ties the beams 23 and 26 and one of the timbers 24 to the timber 29 and the rod 18 ties the parts 23 and 26 and one of the timbers 24. The timber 29 is a portion of the main supporting frame, and the frame which supports the rail to be straightened is securely tied and braced to said main frame, the frame work being securely bound together to successfully withstand the thrust when the machine is in operation.

The guide 14 for the cross head 13 is secured at one end by a bearing 32 fastened to the side of the timber 29, and at the other end by a support 33 carried by the flanged base 30 of the cylinder 10.

Steam or other fluid pressure is admitted to the cylinder through a valve chest 34 containing a suitable hand-controlled valve connected by a rod 35 to a hand lever 36 located at such a point on the frame work that the operator can watch the work.

The machine is simple, cheap, efficient and rapid. The ram can be instantly stopped at any point in the stroke, and the pressure to be applied to the rail or other part to be straightened can be readily varied and controlled by admitting more or less fluid pressure to the cylinder. The ram head will be shaped to suit the work to be straightened, and it is detachably connected to the ram so that it may be changed for one suited for the particular part to be straightened.

While the preferred embodiment of the machine has been shown, it will be understood that various changes and modifications in the structural details thereof may be made without a departure from the spirit and scope of the invention as claimed herein-after.

I claim—

1. A machine of the character described comprising a reciprocatory bending ram having a working head, a pair of parallel spaced beams, work-supporting means positioned between the beams, a guide on one of the beams through which the ram passes, a lever fulcrumed at one end, actuating means for the lever connected to the other end thereof, a connection between the ram and the lever intermediate the ends of the latter, and a rigid tie rod connecting the aforesaid beams and projecting laterally from one of said beams, to which projecting end of the rod the lever is fulcrumed.
- 10 2. A machine of the character described comprising a reciprocatory bending ram, a fluid pressure cylinder, a piston in the cylinder, a sliding cross head connected to the

piston, a lever fulcrumed at one end and 20 having its other end connected to the cross head, and a connection between the ram and the lever intermediate the ends of the latter.

3. A machine of the character described, comprising a reciprocatory bending ram 25 having a working head, a pair of parallel spaced beams, work-supporting means positioned between the beams, a guide on one of the beams through which the ram passes, a lever fulcrumed at one end, actuating means for the lever connected to the other end thereof, a connection between the ram and the lever intermediate the ends of the latter, and a rigid tie-rod projecting laterally from one of said beams, to which projecting end 30 of the rod the lever is fulcrumed.

In testimony whereof I affix my signature.
WILLIAM KEELY.
